UNITED STATES PATENT OFFICE.

EDUARD VON SALIS, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

FUEL-INJECTION DEVICE FOR INTERNAL-COMBUSTION ENGINES.

Application filed November 12, 1924, Serial No. 749,375, and in Switzerland December 11, 1923.
Renewed July 25, 1927.

The invention relates to so-called airless injection engines and its object is to provide an airless fuel injection device having associated therewith an accumulator subject to the pressure of the fuel and adapted and arranged to exercise also another function or functions. The invention is an improvement on the fuel injection device disclosed in the application of Eduard von Salis, Serial Number 747,706, filed Nov. 4, 1924, but differs therefrom in that no spring other than the accumulator spring itself is required, and in that the construction is such that increase of fuel pressure on the accumulator spring presses the valve the more tightly on its seat. The device possesses other distinctive advantages hereinbelow pointed out or made apparent to those skilled in the art.

Referring to the drawing the single figure 20 is a vertical section through the preferred form of the fuel injection device, a conventional fuel pump being shown on reduced scale in elevation.

In the embodiment of the invention illustrated, the cylinder 1 is provided with the usual cavity for the reception of the fuel injection device having the two part valve casing 2, 3, the member 2 of which contains the fuel injection opening 5 to the cylinder or to a precombustion chamber served through piping and ducts 6 by the usual pump 7 adapted to give variable delivery to suit current engine requirements. The injection opening 5, which may be, but need not be, the injection nozzle or final outlet to the engine cylinder is controlled by the needle valve 8, preferably, though not necessarily, of the spring-closed and fuel-pressure-opened type, and whose stem 9 is shown 40 as enclosed by an accumulator plunger-sleeve 10 slidable with respect to and closely fitting both the stem 9 and a cavity in the member 2 of the valve casing. A spring 11, both ends of which in the preferred form 45 are movable, and which constitutes both the accumulator spring and the sole active means for closing the valve and for holding it on its seat, is centered by and reacts between the abutment 12 slidable in the bore of 50 the member 3 of the valve casing and the flange 13 of the sleeve 14 screw threaded to the accumulator plunger-sleeve, and by thrusting against both holds the valve 8

normally closed. The annular shoulders 15 of the sleeve 14 and 16 of the valve stem 9 55 coact to this end. The back-thrust of the spring 11 is transmitted by the sliding abutment 12 to the intermediate lever 17 mounted on the valve casing and carrying the anti-friction roller 18 through which it in turn 60 transmits the thrust to the arm 19 of the cam lever 20 also pivotally mounted on the top of the valve casing and whose arm 20 bears upon the end of the extended valve stem 9 thereby preventing opening of the 65 valve by fuel pressure on the shoulder 21 except when the mechanical obstruction just described is removed by action of the cam 22 on the cam roller 23 of the lever 19, 20. This release puts the accumulator 70 spring under still further compression, but occurring at a time when the fuel pressure has raised the accumulator plunger so as to disengage the shoulder 15 from the shoulder 16 leaves the valve free for fuel pressure opening, whereupon the accumulator plunger gives a quick sharp injection of the fuel and again closes the valve through action of the shoulders 15, 16. 75

It will be seen that by this construction 80 danger of premature opening of the valve, which otherwise might occur if the normally permissible oil pressure were exceeded before the fuel valve was unblocked, is obviated without the necessity for using a second 85 spring, and that increase of fuel pressure instead of reducing the spring pressure available to hold the valve to its seat, as in the embodiment of the other application above referred to, increases the pressure 90 having that effect. The device is also provided in the sleeve-extension 24 with stop means cooperating with the abutment 12 and associated lever mechanism for limiting the extent of spring compression to a permissible 95 maximum and for thereafter positively holding the valve on its seat even under the most extreme fuel pressure conditions or when the charge completely fills the fuel chamber, enlarged to the fullest extent, and the associated ducts. It will be understood 100 that a change of tension of the accumulator spring may be effected in any of several ways, for example by arranging an adjusting device on the lever 17 or a set screw on the arm 19 of the lever 20. 105

The pressure surface of the plunger available to effect its outward movement exceeds that of the valve, so that there is no possibility of the latter rising at the same time as the former, or before the accumulated energy has reached the requisite high point, and this notwithstanding that the valve has a favorable leverage on the spring in lever 17.

The foregoing description in detail of the form of the device illustrated must not be regarded as limiting the invention beyond its true scope which is designed to be set forth in the claims, since it is recognized that the invention may be otherwise embodied.

I claim:

1. An airless fuel injection device for internal combustion engines comprising a fuel injection opening, a valve controlling said opening, and an accumulator subject to pressure of the fuel charge and operatively connected to said valve so as to press it the more tightly on its seat the higher the accumulator pressure rises.
2. An airless fuel injection device for internal combustion engines comprising a fuel injection opening, a valve controlling said opening, means for opening said valve, means for temporarily blocking the valve against opening, and an accumulator having a plunger subject to the pressure of the fuel charge and acting simultaneously as an accumulator and to seat said valve.
3. An airless fuel injection device for internal combustion engines comprising a fuel injection opening, a valve controlling said opening, means for opening said valve, means for blocking the valve against opening, means for unblocking the valve, and an accumulator subject to pressure of the fuel charge and operative connections between said accumulator and said blocking means, and through said blocking means to the valve, said accumulator acting simultaneously as an accumulator and, through said connections, to urge the blocking means toward blocking position and the valve toward its seat.
4. An airless fuel injection device for internal combustion engines comprising a fuel injection opening, a valve controlling said opening, an accumulator subject to pressure of the fuel charge, two means of operative connection between the accumulator and the valve, one of them interrupted on accumulator compression, and cam operated means for controlling the other.
5. An airless fuel injection device for internal combustion engines comprising a fuel injection opening, a valve controlling said opening, means for opening said valve, means for temporarily blocking the valve against opening, means for unblocking the valve, and an accumulator subject to the pressure of the fuel charge, operative connections be-

tween said accumulator and the valve blocking means exerting back pressure of the accumulator thereon, and other operative connections between the accumulator and the valve exerting return pressure of the accumulator thereon, said accumulator being adapted to act as an accumulator and also by virtue of said connections as a means for urging the blocking means into blocking position, and as a seater for the valve. 75

6. An airless fuel injection device for internal combustion engines comprising a fuel injection opening, a valve controlling said opening, means for opening said valve, means for temporarily blocking the valve against opening, including a cam lever, a cam adapted to actuate said lever to unblock the valve, and an accumulator spring subject to the pressure of the fuel charge, operatively connected to the valve blocking means and acting simultaneously as an accumulator, to seat said valve, and to urge the cam lever toward the cam. 80

7. An airless fuel injection device for internal combustion engines comprising a fuel injection opening, a valve controlling said opening, means temporarily blocking the valve against opening, an accumulator subject to the pressure of the fuel charge and on its compression movement acting simultaneously as an accumulator and as means for urging the blocking means toward blocking position, and operative connections between said accumulator and blocking means through which the accumulator acts. 90 100

8. An airless fuel injection device for internal combustion engines comprising a fuel chamber having a fuel injection opening, an accumulator plunger subject to pressure of the fuel, and a valve controlling said opening and acting as a stop for the accumulator in both directions of its movement. 105

9. An airless fuel injection device for internal combustion engines comprising a fuel injection opening, a valve controlling said opening, means for blocking the valve against opening, means for unblocking the valve, an accumulator spring subject to the pressure of the fuel charge, means for compressing both ends of the accumulator spring at the moment of unblocking the valve, and valve opening means for thereupon releasing the accumulator to its fuel injection stroke. 110 115

10. An airless fuel injection device for internal combustion engines comprising a fuel injection opening, a valve controlling said opening, an accumulator plunger subject to the pressure of the fuel charge, a movable abutment for said accumulator receiving the back thrust of the accumulator spring and transmitting it to the valve through operative connections, thereby pressing the fuel valve upon its seat the harder, the higher the accumulator pressure rises. 120 125

11. An airless fuel injection device for 120

internal combustion engines as set forth in claim 10 and in which the operative connection between the accumulator spring and valve is a lever transmission.

- 5 12. An airless fuel injection device for internal combustion engines comprising a fuel injector opening, a valve controlling said opening, an accumulator plunger subject to the pressure of the fuel, and a movable abutment for said accumulator receiving its back thrust and operatively connected to the valve, said plunger and abutment having cooperating stop portions limiting the compression of the accumulator spring and 10 on the limit of compression being reached acting as rigid connections to transmit any further thrust.

13. An airless fuel injection device for internal combustion engines comprising a fuel injection opening, a valve controlling said opening, an accumulator plunger and an accumulator spring associated therewith, the ends of said spring being movable in opposite directions, and operative connection between both ends of the spring and said valve tending to seat the same.

14. An airless fuel injection device for internal combustion engines comprising a fuel injection opening, a valve controlling said opening, and an accumulator spring subject to the pressure of the fuel charge, operatively connected to said valve and constituting the sole active means urging the same toward its seat.

35 15. An airless fuel injection device for internal combustion engines, removable and replaceable as a unit in the cylinder wall and having a valve casing, a fuel chamber therein having a fuel injection opening, a valve controlling said opening, an accumulator plunger and spring surrounding said valve in said casing, said spring acting against a movable back-thrust plate in the casing and a lever transmission for transmitting said back-thrust from said plate to the valve.

50 16. An airless fuel injection device for internal combustion engines comprising a fuel injection opening, a valve controlling said opening, means for opening said valve, means temporarily blocking the valve against opening, an accumulator spring, both ends of which are movable, and one end of which is subject to the pressure of the fuel charge, means for transferring the movement of the other end of the spring to said blocking means while by virtue of movement of the end first named it is acting as an accumulator.

60 17. An airless fuel injection device for internal combustion engines comprising an injection valve, an accumulator spring subject to the pressure of the fuel charge, a valve lever, and a cam, the valve lever being urged toward the cam by the accumulator.

18. An airless fuel injection device for internal combustion engines comprising a fuel injection opening, a valve controlling said opening, a valve-seating and valve-blocking accumulator associated with the valve, and adapted to be displaced by the fuel to store up energy, and engine driven means for periodically unblocking the valve from the accumulator at a time when the pressure of the fuel has otherwise freed the valve from valve seating pressure of the accumulator.

19. An airless fuel injection device for internal combustion engines comprising a fuel injection opening, a fuel-pressure-opened valve controlling said opening, means blocking said valve against opening by fuel pressure, and an accumulator subject to the pressure of the fuel and adapted to act simultaneously as an accumulator and to urge the blocking means into position to block the valve.

20. An airless fuel injection device for internal combustion engines comprising a fuel injection opening, a valve controlling said opening, and an accumulator spring subject to displacement by pressure of the fuel and acting on the valve to seat the same while acting as an accumulator.

21. In an airless fuel injection device for internal combustion engines, a valve member controlling a fuel injection opening, an accumulator spring initially loading said valve and subject to displacement by pressure of the fuel, means for opening the valve, means operatively connected to the accumulator spring for blocking the valve against opening, and engine operated means for unblocking the valve and putting the accumulator under further compression as it unloads the accumulator from the valve.

22. An airless fuel injection device for internal combustion engines having a fuel injection opening, a valve member controlling said opening, an accumulator spring both of whose ends are movable by the application of pressure thereto, means to apply fuel pressure to one end, engine driven cam means for periodically applying pressure to the other end, and means for opening the valve during such periodic application.

23. An airless fuel injection device for internal combustion engines comprising a fuel injection opening, a valve controlling said opening, an accumulator spring subject to displacement by pressure of the fuel, and means for compressing both ends of the accumulator spring at the moment of its release to its injection stroke.

24. A fuel injection device for internal combustion engines comprising a fuel injection opening, a valve controlling said opening, an accumulator spring operatively connected to the valve and subject to displacement by fuel pressure, both ends of

- 4
- said spring being movable, and acting simultaneously as an accumulator and to seat the valve.
25. An airless fuel injection device for internal combustion engines comprising a fuel chamber having a valve-controlled injection opening, an accumulator plunger and a valve in said fuel chamber, both subject to movement by the fuel pressure, and a single spring means acting to restrain such movement, the pressure area of the plunger exceeding that of the valve.
26. A fuel injection device for internal combustion engines comprising a fuel injection opening, a valve seat surrounding said opening, a valve seating thereon, an accumulator subject to displacement by fuel, and means of connection between the accumulator and valve including a lever.
- 20 27. A fuel injection device for internal combustion engines comprising a fuel injection opening, a valve seat surrounding said opening, a valve seating thereon, an accumulator subject to displacement by fuel, an engine-driven cam, a cam lever coacting therewith, and means of operative connection between said accumulator and cam lever including another lever.
- 30 28. A fuel injection device for internal combustion engines according to claim 26 in which the accumulator is operative through said connection to load the valve during the accumulation of energy.
- 35 29. A fuel injection device according to claim 26 in which there is an engine driven cam and a cam lever coacting therewith and in which the accumulator is operative on the cam lever during the release of accumulated energy to urge it toward the cam.
- 40 30. A fuel injection device for internal combustion engines comprising a fuel injection opening, a valve seat surrounding said opening, a valve seating thereon, an accumulator subject to displacement by fuel, a valve-blocking connection from the accumulator to the valve, a lever in said connection, and means for opening the valve.
31. A fuel injection device for internal combustion engines comprising a fuel injection opening, a valve seat surrounding said opening, a valve seating thereon, and an accumulator subject to displacement by fuel and operatively connected to said valve so as to press it the more tightly on its seat the higher the accumulator pressure rises.
32. A fuel injection device for internal combustion engines comprising a fuel injection opening, a valve seat surrounding said opening, a valve seating thereon, an accumulator subject to displacement by fuel and operatively connected to said valve, a valve-blocking connection from the accumulator to the valve whereby the accumulator presses the valve the more tightly on its seat the higher the accumulator pressure rises, means for periodically unblocking the valve, and means for opening the valve.
33. A fuel injection device for internal combustion engines comprising a fuel injection opening, a valve seat surrounding said opening, a valve seating thereon, an accumulator spring loading the valve and subject to displacement by fuel, a valve-blocking connection from the accumulator to the valve, means for periodically unblocking the valve, and means for opening the valve.

In testimony whereof, I have signed this specification.

EDUARD von SALIS.
